US00D998478S

(12) **United States Design Patent** (10) **Patent No.:** **US D998,478 S**
(45) **Date of Patent:** **** Sep. 12, 2023**

(54) **GAS MONITORING DEVICE**

- (71) Applicant: **Industrial Scientific Corporation**,
Pittsburgh, PA (US)
- (72) Inventors: **Charles Dennis Hughes**, Moon
Township, PA (US); **Thomas Michael
Mikulin**, New Wilmington, PA (US);
Henry J. Suwalski, Cranberry
Township, PA (US); **Adrian Sirbu**,
Coraopolis, PA (US)

- (73) Assignee: **Industrial Scientific Corporation**,
Pittsburgh, PA (US)

(**) Term: **15 Years**

(21) Appl. No.: **29/723,232**

(22) Filed: **Feb. 5, 2020**

Related U.S. Application Data

- (63) Continuation of application No. 29/551,639, filed on
Jan. 15, 2016, now abandoned.
- (51) **LOC (14) Cl.** **10-04**
- (52) **U.S. Cl.** **USPC .....** **D10/66**
- (58) **Field of Classification Search**

(57) **CLAIM**

The ornamental design for a gas monitoring device, as shown and described.

DESCRIPTION

FIG. 1 is a front perspective view of a gas monitoring device;

FIG. 2 is a front view thereof;

FIG. 3 is a rear view thereof;

FIG. 4 is a left side view thereof;

FIG. 5 is a right side view thereof; and,

FIG. 6 is a top view thereof.

The broken lines shown in the figures show portions of a gas monitoring device that form no part of the claimed design.

1 Claim, 6 Drawing Sheets
